UNITED STATES PATENT OFFICE.

DAVID L. WINTERS, OF CHICAGO, ILLINOIS.

FIRE-ESCAPE.

SPECIFICATION forming part of Letters Patent No. 605,686, dated June 14, 1898.

Application filed February 28, 1898. Serial No. 672,092. (No model.)

To all whom it may concern:

Be it known that I, DAVID L. WINTERS, a citizen of the United States, residing at Chicago, in the county of Cook and State of Illinois, have invented certain new and useful Improvements in Fire-Escapes; and I do hereby declare the following to be a full, clear, and exact description of the same, reference being had to the accompanying drawings, forming a part of this specification.

This invention relates more especially to that type of automatic fire-escapes in which the lowering-rope passes over a sheave or pulley the shaft of which has connection with a friction device that by centrifugal action governs the rotation of the sheave or pulley and causes the same to be of a uniform nature regardless of the weight of the descending person or load, the object of the present improvements being to provide a simple, cheap, and durable mechanism for such uses that is capable of effective operation in either direction, so that after one person or load has been lowered the opposite end of the lowering-rope will be in position ready for lowering another person, all as will hereinafter more fully appear, and be more particularly pointed out in the claims. I attain such object by the construction and arrangement of parts illustrated in the accompanying drawings, in which—

Figure 1 is a view, partly in section, at line $x x$, Fig. 2, the main portion of one of the counterpart halves of the housing being removed, with portion of the sheave or pulley in elevation and with the friction-shoes in section; Fig. 2, a transverse section at line $x' x'$, Fig. 1; Fig. 3, a side elevation of the combined sheave and friction-shoe carrier of the present improvement; Fig. 4, an end elevation of the same; Fig. 5, a side elevation of one of the friction-shoes, and Fig. 6 a top view of the same.

Similar numerals of reference indicate like parts in the several views.

As represented in the drawings, the housing or casing of the present mechanism will consist of two counterpart halves 1 and 1 and each formed with a web or head portion 2, a concentric cylindrical rim portion 3, a centrally and inwardly projecting tubular neck or portion 4, a suspension-loop 5, a tubulous

guide-lug 6 for the fire-escape rope or cable, and marginal lugs 7, by means of which the sections are bolted together in a fixed and substantial manner.

The tubular necks 4 of the housing taken together form the journal-arbor for the rope-sheave of the present invention. Such rope-sheave composes a main sheave portion 8, formed with a centrally-arranged peripheral groove 9 to receive and retain the lowering rope or cable looped around the sheave, as shown, the central portion of said sheave being provided with the usual hub portion 10, turning on the tubular necks 4 of the casing and having sufficient length to prevent end-wise movement of the sheave within the casing when the parts are connected together for use.

Equidistantly from the medial line and in a transverse direction the sheave 8 is formed or provided with duplicate series of radial projections 11, of a thin and rectangular form, that constitute slideways or guides for the duplicate series of friction-shoes of the present invention.

The duplicate series of friction-shoes 12 have a sector-shape formation, with radial guide-orifices 13, that are adapted to engage upon the respective guide projections 11 of the sheave, so as to have a radial movement thereon in the operation of the mechanism, and in my preferred construction, as shown in the drawings, the orifice 13 in the said shoes will be of a greater length than the projections 11, so that there will be some lost motion before said projections engage the forward ends of said openings in the operation of the mechanism, the purpose of this arrangement being to permit of a slight initial movement of the sheave and lowering-cable before the friction-shoes are brought into action, as I find by practical test that such construction affords greater sensitiveness as well as safety to the apparatus.

14 is the lowering-cable, of any usual form and material and which is adapted to pass around the sheave and out through the pair of guide-orifices in the tubular lug 6 of the casing, as shown.

In use with the descent of a person or load upon one side or end of the cable an acceleration in the speed of descent will cause the

series of friction-shoes to move out by centrifugal action into frictional contact with the interior cylindrical surface of the housing to retard and resist such action, the amount of friction set up corresponding with the speed of descent, so that by a proper proportioning of the parts the load or person will descend at a uniform and slow speed regardless of the weight of such load or person.

10. Having thus fully described my said invention, what I claim as new, and desire to secure by Letters Patent, is—

15. 1. In a fire-escape, the combination of an in-closing casing provided with an interior cylindrical track-surface, a sheave mounted to rotate within said housing and provided with duplicate series of radial guide projections, and a rope-groove arranged centrally between said series of projections, and duplicate series of friction-shoes arranged to slide radially on said projections and adapted to contact with the cylindrical track-surface of the housing, substantially as set forth.

20. 2. In a fire-escape, the combination of an in-closing casing formed in counterpart halves, each provided with a central tubular neck and an interior cylindrical track-surface, a sheave arranged to rotate on said necks and

provided with duplicate series of radial projections, and with a rope-groove arranged centrally between said series of projections, and duplicate series of friction-shoes arranged to slide radially on said projections and adapted to contact with the cylindrical track-surface of the housing, substantially as set forth.

3. In a fire-escape, the combination of an in-closing casing formed in counterpart halves, each provided with a central tubular neck, marginal connecting-lugs, tubular guide-lugs, suspension-lug and an interior cylindrical track-surface, a sheave arranged to rotate on said necks and provided with duplicate series of radial projections, and with a rope-groove arranged centrally between said series of projections, and duplicate series of friction-shoes arranged to slide radially on said projections, and adapted to contact with the cylindrical track-surface of the housing, substantially as set forth.

In testimony whereof witness my hand this 26th day of February, 1898.

DAVID L. WINTERS.

In presence of—
JAMES LAVALLIN,
ROBERT BURNS.
